Primary Examiner — Paula Allen Greene

(74) Attorney, Agent, or Firm — Michael Best & Friedrich LLP

(57) **CLAIM**

I claim the ornamental design for an earbud, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front perspective view of an earbud in accordance with an embodiment of the invention.

FIG. 2 is a front view of the earbud of FIG. 1.

FIG. 3 is a top view of the earbud of FIG. 1.

FIG. 4 is a right-side view of the earbud of FIG. 1.

FIG. 5 is a left-side view of the earbud of FIG. 1.

FIG. 6 is a front perspective view of an earbud in accordance with another embodiment of the invention.

FIG. 7 is a front view of the earbud of FIG. 6.

FIG. 8 is a top view of the earbud of FIG. 6.

FIG. 9 is a right-side view of the earbud of FIG. 6; and,

FIG. 10 is a left-side view of the earbud of FIG. 6.

The letters "MILW" with partial lightning bolt beneath forming part of the claimed design is a portion of a registered trademark of Milwaukee Electric Tool Corporation.

**1 Claim, 4 Drawing Sheets
(4 of 4 Drawing Sheet(s) Filed in Color)**
